UNITED STATES PATENT OFFICE.

HAROLD BLYE, OF GRAND RAPIDS, MICHIGAN, ASSIGNOR TO NATIONAL BRASS COMPANY, OF GRAND RAPIDS, MICHIGAN, A CORPORATION OF MICHIGAN.

LOCK SET.

1,399,538.

Specification of Letters Patent. Patented Dec. 6, 1921.

Application filed January 13, 1919. Serial No. 270,936.

To all whom it may concern:

Be it known that I, HAROLD BLYE, a citizen of the United States of America, residing at Grand Rapids, in the county of Kent and State of Michigan, have invented 5 certain new and useful Improvements in Lock Sets; and I do hereby declare the following to be a full, clear, and exact description of the invention, such as will 10 enable others skilled in the art to which it appertains to make and use the same.

This invention relates to a lock set adapted particularly for use on swinging doors either separately or in conjunction with my 15 invention entitled Latch set, for which I have made application for patent separately. It is an object and purpose of the present invention to provide a lock set which may be very easily and readily applied to doors by unskilled labor, requiring 20 little time for installation, where, heretofore it has been common to make use of a combined lock and latch of such form that relatively large openings had to be mortised 25 in the door to receive the same, skilled wood workers being required to properly do the work and a much longer time being taken than with the construction of my invention with which one hole need be bored with an 30 auger or bit for the lock set and another for the latch set, the same receiving the entire lock and latch installation. A further object of the invention is to produce a very simple and compact construction, manufactured at very low cost, one in which the 35 parts making up the device may be readily assembled or disassembled to replace or repair any part which may become broken or otherwise out of working order, and one in 40 which a relatively long throw of the locking bolt may be had in a very small cylindrical housing which is necessary for the device if it is to be received between the front and rear sides of a door and housed 45 completely therebetween. All of these objects and purposes together with novel constructions and arrangements of parts to effect the same, as well as many others not at this time specifically set forth, will 50 appear fully and in detail as understanding of the invention is had from the following description taken in connection with the accompanying drawing, in which,

Figure 1 is a partial plan and sectional

view of the lock set applied to a door, the 55 door and key guide being in horizontal section and the lock set in plan.

Fig. 2 is an enlarged side elevation of the lock set, one of the housing members being removed to show the interior mechanism in 60 the position it occupies when the bolt is retracted.

Fig. 3 is an enlarged plan of the latch bolt and connected operating mechanism.

Fig. 4 is an enlarged vertical section 65 taken longitudinally at the inner end of the bolt.

Fig. 5 is a fragmentary enlarged side elevation of the inner end of the bolt and operating mechanism therefor, the same 70 occupying an intermediate position between the extended and retracted positions of the bolt.

Fig. 6 is a rear elevation of the key guide 75 escutcheon.

Fig. 7 is an elevation of the end of the key used to operate the lock.

Like reference characters refer to like parts in the different views of the drawing.

The lock set is adapted to be applied at 80 the free vertical edge of a door 1, in which a cylindrical opening 2 is bored to receive the set. The lock set is also of cylindrical form, preferably, including in its construction two semi-cylindrical housing members 85 3 and 4 which, when placed together, form a cylinder in which the lock set mechanism is housed. Each member 3 and 4 is provided at each end with a short pin 5 to pass into bayonet slots 6 cut in opposite sides of 90 a rear cap 7 and a front sleeve 8, the latter being permanently secured to a face plate 9 which is adapted to lie against and which, preferably, is set in the vertical edge of the door. The housing thus constructed is substantially the same as that for the latch set differing only in that the opening in the plate 9 to pass the lock bolt is of different shape and in that each of the members 3 and 4 are pressed inwardly as indicated at 100 10 at a point between their ends.

At such inwardly pressed portions 10, each housing member 3 and 4 is formed with an opening to receive the ends 11 of a rotatably mounted lock bolt operating 105 member, the middle part 12 of which is of smaller diameter and between which and the ends 11 collars 13 of larger diameter are po-

sitioned as shown in Fig. 3. Said operating member is slotted at diametrically opposed points as shown at 14 so that the same may be engaged by a key 15 having two tangs 16 separated far enough that the same may freely enter the two slots at the ends of said operating member, the key being utilized to turn the operating member. An arm 17 extends from the central section 12 as shown and moves with the operating member when it is rotated.

The lock bolt 18 is formed from sheet metal into cylindrical form at its outer end being thence cut away and narrowed to form a rear extension 18^a which passes under the central section 12 of the operating member and between the collars 13. At its rear end said extension is provided with two upstanding spaced apart ears 19 between which downwardly extending ears 20 at the rear end of a connecting link 21 pass, a pivot pin 22 passing through the ears and pivotally connecting the link and lock bolt. At its front end link 21 has pivotal connection with the arm 17, a pivot pin 23 being used. A spring 24 is coiled around pin 22, its free arms engaging with the ends of link 21 and the extension 18^a, the normal tendency of which is to force the front end of link 21 and the end of the arm 17 toward the extension 18^a as will be obvious.

The rotation of the rotatably mounted operated member by the key causes the arm 17 to move from the position it occupies in Figs. 2 and 3 to the position indicated in Fig. 1. When the arm turns from rear to front position the link 21 moves with it, causing a corresponding movement of the lock bolt whereby it is moved from its retracted position in which it is entirely housed within the housing to extended position as shown in Fig. 1, the bolt entering any suitable opening in the adjacent door casing and locking the door against movement. In Fig. 5 the position of the parts is shown when the rotative movement of the operating member is about half completed and the lock bolt has been started toward its extended or projected position. The action is easy, the bolt being very quickly and positively operated. When the bolt is once fully projected it is impossible to force the same back by pressure against the end of the bolt as the line of force thus applied passes directly through or above the axis of pivot 23, causing, if anything, a more secure retention of the projected position of the bolt. The spring 24 helps to keep the bolt in place against any accidental rotative movement of the operating member which might occur if no force was present to stop such rotation. The throw of the bolt is large compared to the limited space in which the mechanism must work, in fact fully as large as in any of the lock sets used. The mechanism is

simple and compact and made of parts all of which with the exception of the rotating operating member, may be made entirely from sheet metal, and this part is easily made in quantities at low cost as a die casting. 70 This member may be varied in many respects so far as the slots 14 are concerned to provide many different key changes. For instance the slots may be made of greater or less depth, or may be entirely dispensed with and 75 some other form of key engaging recess provided in the ends of the operating member for the different key changes which should be included in any practical lock. All of these features make the lock one of practical 80 value and particularly as, in addition, the installation is done in such an easy manner, requiring merely that a hole of a size to receive the cap 7 and sleeve 8 shall be bored in the edge of the door deep enough that the 85 housing can be fully inserted.

Of course an opening must be provided for the insertion of the key for operation of the lock and it is desirable that this opening be covered and that a suitable guide for the 90 key provided. I have provided both of these in a combined covering escutcheon plate and key guide rotatably mounted thereon. The escutcheon plate 25 may be of any suitable design, preferably, having a raised portion 95 in which a central opening 26 is cut, said opening being made in a depressed central part of the plate. The key guide 27 is formed from thin sheet metal into rectangular form for ready passage of the key and from the 100 sides of said key guide two tangs 28 are cut and turned to bear against the inner side of the plate 25 adjacent the edges of the opening 26. Likewise the outer end of the key guide has tangs 29 turned to lie against 105 the outer face of plate 25, said tangs 29 being, preferably, rounded so as to cover the opening 26. This construction permanently attaches the key guide to the plate 25 but permits the same to rotate with the key when 110 it is connected with the operating member of the lock set.

While the plate 25 is shown attached at one side only of the door, it is obvious that it may be duplicated for the opposite side 115 of the door if it is desired to operate the lock by a key from both sides. In this construction, I have shown an escutcheon plate complete for the lock set, but in practice, when the lock set is used in conjunction with the latch set it may be advisable to use one escutcheon on each side of the door for both the lock and latch sets, this being a matter of preference and not in any way affecting the merits of the two inventions. For the purpose of obtaining the greatest throw of the lock bolt and as long an arm 17 as possible to get such throw, I prefer to cut the adjacent edges of the housing members 120 3 and 4 at their upper sides above the arm 130

as indicated at 30, making a slot in the completed housing which gives more room for the operation of the mechanism.

The construction described is a complement to and is particularly useful in conjunction with my other invention of latch set to which reference has been made. In actual practice it has been demonstrated that an hour's time of a skilled mechanic may be saved in installation of the latch and lock set over the usual forms of combined locks and latches for doors in dwelling houses or the like, while the cost of manufacture of this invention is below that of other articles designed to serve the same purposes. The efficiency and durability of the construction is obvious.

I claim:

In a device of the character described, an elongated housing, an operating member

provided with key receiving recesses in each end thereof rotatably mounted transversely of and within the housing, a locking bolt formed of sheet metal located lengthwise of the housing and extending at its rear end under the operating member and formed with two upstanding ears at its rear end, an arm projecting from the operating member, a link formed into substantially channel form from sheet metal pivotally connected at its front end to the arm and at its rear end passing downwardly between the ears of the bolt, a pivot connecting the rear end of the link and said ears, and spring means disposed between the link and rear end of the bolt tending to force the front end of the link toward the bolt, substantially as described.

In testimony whereof I affix my signature.

HAROLD BLYE.
